(57) **CLAIM**

The ornamental design for a locking sleeve, as shown and described.

DESCRIPTION

FIG. 1 is a front, right, top perspective view of a locking sleeve showing our new design;

FIG. 2 is a rear, left, bottom perspective view thereof;

FIG. 3 is a front, left, bottom perspective view thereof;

FIG. 4 is a front elevation view thereof;

FIG. 5 is a rear elevation view thereof;

FIG. 6 is a right side view thereof, with the left side view being a mirror image thereof;

FIG. 7 is a top plan view thereof; and,

FIG. 8 is a bottom plan view thereof.

The broken lines of even length shown in the drawings depict portions of the locking sleeve that form no part of the claimed design.
